UNITED STATES PATENT OFFICE.

ISAAC NEWTON FELTENBERGER, OF CARNEGIE, PENNSYLVANIA.

FENCE.

SPECIFICATION forming part of Letters Patent No. 606,527, dated June 28, 1898.

Application filed August 12, 1897. Serial No. 648,020. (No model.)

To all whom it may concern:

Be it known that I, ISAAC NEWTON FELTENBERGER, a citizen of the United States, residing at Carnegie, in the county of Allegheny and State of Pennsylvania, have invented certain new and useful Improvements in Fences; and I do hereby declare the following to be a full, clear, and exact description of the invention, such as will enable others skilled in the art to which it appertains to make and use the same.

This invention relates to fences; and the object in view is to provide a sectional fence in which the panels may be individually removed from engagement with the fence-post, so as to enable access to be had to a field at any desired point thereof.

The improved fence embodies a novel construction of post adapted to be formed wholly of metal and embodying supporting means whereby it is prevented from sinking and sagging or listing to one side, thus providing for maintenance of the fence in proper position.

The detailed objects and advantages of the invention will appear in the course of the subjoined description.

The invention consists in an improved sectional fence embodying certain novel features and details of construction, as hereinafter fully described, illustrated in the drawings, and incorporated in the claims hereto appended.

In the accompanying drawings, Figure 1 is a side elevation showing a section of fence constructed in accordance with the present invention. Fig. 2 is a detail view of one of the fence-panels. Fig. 3 is a sectional view showing the improved fence-post. Fig. 4 is a detail perspective view of the fence-post. Fig. 5 is a plan view of the upper keeper-plate. Fig. 6 is a similar view of the lower supporting-plate.

Similar numerals of reference designate corresponding parts in all the views.

Referring to the drawings, 1 designates one of the fence-panels, which comprises, essentially, a rectangular frame embodying upper and lower parallel rails 2 and end uprights 3. The open center of this frame may be covered by any suitable fabric, barbed wire, as indicated at 4, or pickets, as may be preferred. In carrying out the present invention

each of the end uprights 3 is provided with L-shaped irons 5, each having a depending pintle 6, adapted to enter eyes on the post. 55

The fence-post (indicated at 7) is in the form of a rod or vertical standard of any suitable shape in cross-section and provided adjacent to its upper and lower ends with oppositely-projecting eyes 8, the said eyes being arranged at suitable elevations for receiving the pintles 6 of the panels. At a point intermediate to its ends the post 7 is provided with an abrupt transverse offset 9, adapted to rest upon the ground, the post being extended below said offset, as indicated at 10, to enter the ground for a distance which will obtain the necessary purchase of the post in the ground and prevent the same from listing to one side or the other. Adjacent to the offset 9 and extending in alinement with the upper portion of the post 7 is a depending threaded extension 11, upon which is screwed a plate 12, substantially square in plan and having a central opening which is threaded to adapt it to be adjustably fitted upon the extension 11. This plate 12 is intended to support the post against vertical movement and prevent the same from sinking too far into the ground when the ground becomes moist. The plate 12 may be screwed upward until it bears against the lower side of the offset 9, so that it may rest upon the surface of the ground; but it is preferred to arrange said plate on the extreme lower end of the extension 11 and bury the same beneath the surface of the ground, where it will form just as effective a support for the post without being exposed to view. After the posts 7 are planted the panels 1 are hung thereon by passing the pintles 6 through the eyes 8, and after the panels are in place retaining plates or keepers 13, having screw-threaded openings in their center, are screwed upon the upper threaded ends 14 of the posts, so as to bear 95 against the upper irons 5 and prevent the upward displacement of the pintles 6 from the eyes 8. The plates 13 are preferably oblong, so as to extend at their ends over the irons 5.

From the foregoing description it will be seen that I have provided a simple and economical construction of fence and that one or more of the panels thereof may be readily detached without tools and without affecting

- the remainder of the fence, it being only necessary to take off two or more of the keeper-
5 plates 13. The fence as a whole may be manufactured complete and in sections at the factory. The fence-posts are efficiently supported by means of the plates, which may be either on the surface of the ground or buried beneath the surface thereof, and at the same time the posts are entered into the ground 10 sufficiently to prevent the same from canting to one side or the other. It will also be seen that the posts when the plates 12 are not used may be driven into the ground by striking upon the offset with a suitable sledge.
- 15 One of the chief advantages of the invention resides in the fact that any one of the panels may be quickly and readily detached for enabling the farmer to drive from one field to another, and this will be found of great ad-
20 vantage in harvest-time, enabling the farmer to make a short cut to the barn and obviating the necessity of going a roundabout way in order to pass through the usual gate or drop-bars.
- 25 Having thus described the invention, what is claimed as new, and desired to be secured by Letters Patent, is—
1. In a fence, the combination with posts having oppositely-located eyes, of detachable

panels having pendent pintles adapted to be 30 removably fitted in said eyes, and keeper-plates threaded upon the upper ends of said posts and adapted to prevent upward dis-
placement of said pintles, substantially as de-
scribed.

35 2. A fence-post, consisting of a metal strip bent intermediate to its ends to form a trans-
verse offset and also comprising a pendent extension which projects downward from the offset and forms a continuation of the upper 40 portion of the post, said extension being threaded, and a plate threaded upon said ex-
tension, substantially as and for the purpose described.

3. A fence-post bent intermediate to its ends 45 to form a transverse offset and also comprising a pendent extension below and forming a continuation of the upper portion of the post, and a plate removably fitted upon said ex-
tension, substantially as described.

50 In testimony whereof I have signed this specification in the presence of two subscr-
ing witnesses.

ISAAC NEWTON FELTENBERGER.
